UNITED STATES PATENT OFFICE.

CHARLES F. BALL, OF MILWAUKEE, WISCONSIN, ASSIGNOR TO CHAIN BELT COMPANY, OF MILWAUKEE, WISCONSIN, A CORPORATION OF WISCONSIN.

WATER, POWER, AND SPEED CONTROL MECHANISM FOR CONCRETE-MIXING AND SIMILAR MACHINES.

Application filed April 13, 1927. Serial No. 183,409.

In the operation of concrete mixing machinery it is important, in the interests of large production and proper mixing, that the various operations of the machine should be accurately timed with reference one to the other, in order that there be no unnecessary delays between successive operations. It is also possible in operating concrete mixing machinery to speed up the motor, with a consequent accelerated movement of parts, during certain periods in the cycle of operations being performed, without any resulting harm either to apparatus or the product thereof, and with positive advantage in lessening the time required between the delivery of successive properly mixed batches of material.

My invention has for its object to produce mechanism that may be used in connection with standard types of concrete mixing machinery whereby the delivery of water to the mixing drum is regulated and the speed of the motor that drives the drum and other parts of the apparatus is varied and regulated, all as will be pointed out in the following specification.

In the accompanying drawings Fig. 1 is a side view of a concrete mixing machine of the road paver type to which my invention is applied.

Fig. 2 is a diagrammatic view of the invention, in side elevation, showing parts in different positions from those occupied in Fig. 1.

Fig. 3 is a transverse sectional view taken on the line III—III of Fig. 1.

Fig. 4 is a transverse sectional view taken on the line III—III of Fig. 4.

Fig. 5 is a diagrammatic view in plan showing features of the invention in connection with the water tank.

Referring to the drawings 2 designates the supporting frame of the concrete mixing machine illustrated; 3 the mixing drum thereof, and 4 the loading skip supported on the pivot shaft 5, so that it may be lowered to receive its charge and elevated to deliver the same into the mixing drum in a well known manner. 6 indicates a hand-operated lever for controlling the operations of the clutch through which the skip is connected with a source of power when it is to be elevated to position to deliver into the mixing drum. 7 indicates a water tank such

as is usually employed in connection with concrete mixers of the type illustrated; and 8, the motor, supported on the framework, for rotating the drum and driving the other parts of the machine. The parts thus far described are of usual or approved construction being well known in the art. Many of the parts of the apparatus are not illustrated, or, if suggested in outline, will not be herein described, as they are of well known construction and reference to them is not necessary for an understanding of the present invention.

The motor 8 is provided with a governor or speed control device 9, the particular construction of which is not material to the present invention. 10 indicates a push or slide rod by which the governor is controlled, it being acted upon and moved by lever 11. When the rod 10 is moved in one direction, as to the right in Fig. 1, the governor is controlled or operated so that the speed of the motor will be accelerated.

There is connecting mechanism between the clutch control lever 6 and the lever 11, arranged to operate or control the governor in such manner that the motor may speed up during the elevation of the skip throughout a portion of its rising movement. One form of such connection I will now describe. 12 indicates a link between the hand-operated lever 6 and a bell crank lever 13, that is preferably located below the platform 32, on which the operator of the machine stands. The link 12 is represented as being provided with a foot piece 14 that may be used by the operator to assist in shifting the lever 6, permitting him to move it without direct manual manipulation thereof. The lever 13 is connected with the lever 11, preferably by a flexible cable 15 whose course is directed by one or more pulleys 17. The connection 15 includes a spring 16, which is preferably arranged, as represented, at the end of the connection that is united with the lever 13.

The loading skip is provided with a projection or contact 18 that is adapted to engage with a cam lever 19 pivotally supported at 33 on the framework of the machine. This lever is connected by a link 20 with an arm 31 supported by a shaft 30, that also carries an arm 21, that is connected by a cord 22 with the cable 15. The contact 18

and the cam lever 19 are so related to each other that they do not come into operative engagement until the loading skip has been elevated well towards its charging position. 5 Then the contact comes into engagement with the lever and shifts it with a differential movement that is properly determined by the shape of the cam surfaces of the lever 19 engaged by the contact 18. As the 10 lever is shifted from the position indicated in full lines, Fig. 1, to that represented in dotted lines, same figure, and also represented in Fig. 2, the shaft 30 and the arms 21 and 31 that it carries are oscillated, putting a 15 stress on the cord 22, which is transmitted to the spring 16, which extends, slackening the cord or cable 15 and allowing the lever 11 and operating rod 10 to come to normal position, and permitting the governor to function in its normal automatic manner. The 20 spring 16 is of less strength than is necessary to cause the levers 13 and 6 to be shifted, so that it will yield when the lever 19 is moved by the skip, without imparting motion to the clutch control lever 6, leaving 25 that to be operated independently.

It will thus be seen that the mechanism described insures that the motor shall be automatically speeded up, or supplied with an 30 increased amount of operating force, whatever that be, during the early rising movements of the skip, and then gradually brought back to normal running condition as the skip reaches its final position of discharge, at which instant the connection with the source of power that causes the elevation of the skip is cut off.

I provide also for operating the valves of the water tank 7 through the mechanism 40 which has been described. 24 indicates a lever arranged to control and operate the outlet valve of the water tank, and 25 a lever that controls the inlet valve thereof. These levers are united by a link 26 so they will 45 move together, the link being preferably extensible as to its length to permit easy and accurate adjustment of the valves. The valves are so constructed and arranged that they work alternately, one opening as the 50 other closes and vice versa, and the connections which operate them are such that the discharge valve is opened to permit flow of water to the mixing drum during the period that the skip is in an elevated position and 55 only during that period.

27 indicates a connection between the lever 19 and one of the valve levers of the water tank—the lever 24 in the arrangement illustrated. This connection is represented 60 as being a cord that passes, in its course, over suitable directing and guiding pulleys 28. A spring 29 is interposed in the course of the cord preferably adjacent to its connection with the lever 19. By compressing 65 the spring 29, the valves may be operated

manually through a hand lever 38 connected by linkage to the arm 24 at the point 34. The arm 24 is also connected to a tension spring 35 which normally keeps the discharge valve from the tank closed and the inlet valve open.

As the skip in its upward movements carries the projection 18 into engagement with the cam lever 19, as has been described, the latter is tilted to the position shown in dotted lines, Fig. 1, as the skip approaches its uppermost position. This movement puts stress upon the cord connection 27 sufficient to shift the valves of the water tank, closing the inlet valve and opening the outlet 75 valve to permit the water to be discharged from the tank 7 into the mixing drum.

As the projection 18, on the upward movement of the skip, comes into engagement with the cam lever 19 it first acts upon the 80 forward part 36 of such lever, which is disposed at a sharp angle relative to the path of movement of the projection 18 and causes the valves of the water system to be shifted quickly. After this movement of the valves 85 has fully taken place the projection comes into engagement with a curved surface 37 of the lever 19, which is formed on an arc the radius of which, as the projection 18 90 comes into engagement therewith, extends from the axis 5 about which the skip is turning, so that the further and final upward movements of the skip will impart no motion to the lever; but rather the engagement of the projection 18 with the curved 95 surface 37 of the lever will operate to hold the valves in the position to which they have been moved. Upon the return, lowering, 100 movement of the skip, the lever 19 comes to normal position, as represented in full lines, 105 Fig. 1, and the valves of the water tank are shifted, closing the outlet and opening the inlet, the shifting being effected by automatically operating mechanism, such as a 110 spring 35, in a well known manner.

The lever 19 is arrested in its proper normal position ready to be acted upon by the projection 18 as the skip is again raised, by engagement with a stop 23.

I have illustrated but one embodiment of 115 my invention and wish it to be understood that the invention is not limited to the particular form thereof shown, as various modifications of the invention will suggest themselves to those skilled in the art.

What I claim is:

1. In concrete mixing apparatus, the combination with a motor for driving the same and a charging device therefor, of means for causing acceleration of the speed of the 125 motor during the charging operation.
2. In a concrete mixing apparatus, the combination with the mixing drum, a charging device therefor, and a motor for operating these, of means operating when the 130

charging device is moving to position to charge the drum for causing acceleration of the speed of the motor.

3. In a concrete mixing apparatus, the combination with a mixing drum, a charging device therefor and a motor for operating these, of means arranged to operate, during the initial movements of the charging device toward charging position, to cause acceleration of the speed of the motor, and, during the final movements of such device, arranged to operate to restore the motor to normal running conditions.

4. In a concrete mixing apparatus, the combination with a mixing drum, a charging device therefor, and a motor for operating these, of means that are manually controlled arranged to cause acceleration of the speed of the motor during the initial movements of the charging device toward charging position, and means automatically operated during the final movements of such device and arranged to operate to restore the motor to normal running conditions.

25 5. The combination with a mixing drum, a loading device, a motor provided with a governor device for driving these, and a control lever for the loading device, of a connection between the control lever and the 30 governor device of the motor arranged to move the latter to cause acceleration of the motor when the lever is operated to cause the device to be moved to charging position.

35 6. A combination such as stated in claim 5 characterized by having the connection between the control lever and governor device include a flexible cord.

40 7. A combination such as stated in claim 5 characterized by having the connection between the control lever and governor device include an extensible spring.

45 8. A combination such as stated in claim 5 characterized by having the connection between the control lever and the governor device include a foot piece by which the control lever may be operated.

50 9. The combination with a mixing drum, a loading device, a motor provided with a governor device for driving these, and a control lever for the loading device, of a connection between the control lever and the governor device arranged to move the latter to cause acceleration of the motor when the lever is operated to cause the loading device 55 to be moved toward charging position, and means operated by the loading device for restoring the governor to position for normal operation of the motor as the loader approaches its final position for discharge.

60 10. The combination with a mixing drum, a loading device, a motor provided with a governor device for driving these, and a con-

trol lever for the loading device, of a connection between the control lever and the governor device arranged to move the latter 65 to cause acceleration of the motor when the lever is operated to cause the loading device to be moved toward charging position, a lever operated directly from the charging device as it approaches its final charging position, and connections between said lever and the connections leading to the governor device arranged to restore the latter to normal condition.

11. The combination stated in claim 10 75 characterized by having the lever operated directly from the charging device formed with an operating cam surface whereby it is given a differential movement.

12. The combination with a mixing drum, a loading skip therefor, a motor provided with a governor device for driving these, and a control lever for the loading skip, of connections between the control lever and the governor device including an intermediate lever, a cord between it and the governor device, and a spring between the lever and the cord, a lever operated directly from the loading device as it approaches the limit of its movement toward charging position, 80 and connections between such lever and the said cord including a second cord connected with the first between the spring and the governor device.

13. The combination with a mixing drum, 95 a loading device therefor, a motor provided with a governor device for driving these, a control lever for the loading device, a tank from which water is intermittently discharged to the mixing drum, and inlet and outlet valves for the water tank, of a connection between the control lever and the governor arranged to move the latter to cause acceleration of the motor when the lever is operated to cause the loader to be 100 moved toward charging position, and means operated from the loader for restoring the governor to normal condition as the skip approaches its final position for discharge and also for operating the valves of the water 105 tank to cause delivery of water to the mixing drum.

14. The combination with a rotating drum of a concrete mixing machine, a charging device therefor, and a tank from which 115 water is supplied to the drum, of inlet and outlet valves for the tank, levers connected with the valves for moving them and an extensible link between the levers by which they are caused to move simultaneously and also 120 permitting adjustment of the valves, and means for moving the levers, controlled by the movements of the loading device.

CHARLES F. BALI.
